UNITED STATES PATENT OFFICE.

RONALD K. EVANS, OF ANDERSON, INDIANA, ASSIGNOR TO REMY ELECTRIC COMPANY, OF ANDERSON, INDIANA, A CORPORATION OF INDIANA.

IMPULSE COUPLING.

Application filed November 8, 1921. Serial No. 513,809.

To all whom it may concern:

Be it known that I, RONALD K. EVANS, a citizen of the United States of America, residing at Anderson, county of Madison, State of Indiana, have invented certain new and useful Improvements in Impulse Couplings, of which the following is a full, clear, and exact description.

This invention relates to impulse devices for magnetos, such devices generally constituting a part of the driving mechanism for the magneto, and operating normally to arrest the movement of the magneto armature and then to give to the magneto armature a sudden quick turning movement to produce the maximum current flow for ignition purposes and at the proper time for ignition.

The speed of this impulse or sudden movement of the armature is generally independent of the speed of the magneto operating mechanism, and is accomplished by means of a spring which is wound up or otherwise strained during the time when the armature is restrained from moving; this spring being automatically released at the proper time for ignition. Thus an impulse sufficient for ignition purposes may be imparted to the armature, although the speed of the magneto operating mechanism may be too slow for ignition purposes. Such an impulse device is therefore particularly useful for automobiles in which magneto ignition is employed, and where the engine which drives the vehicle and also the magneto is started by hand or by other device operating at too slow a speed to operate the magneto to produce ignition by the magneto.

Devices of this sort have been produced wherein the impulse spring acts also as a shock absorbing spring to assist in taking up the shock which would come upon the armature due to the operation of the impulse mechanism. A device of this kind is described in the patent to H. O. Putt, No. 1,326,529, patented December 30, 1919. This device employs a helical coil spring as an impulse and shock absorbing or cushioning spring.

While springs of the clock or involute type have been used as impulse springs for impulse devices, so far as I am aware, a volute spring has not been used both as an impulse spring and as a cushioning spring.

It is therefore among the principal objects of the present invention to provide an im-

pulse device for magnetos wherein an involute spring functions both as the impulse spring and as the cushioning spring.

Other and further objects of the present invention will be apparent from the following description, reference being had to the accompanying drawings, wherein a preferred embodiment of the present invention is clearly shown.

In the form of my invention shown herein, the new spring arrangement is shown in connection with a magneto impulser shown in my Patent No. 1,287,659, patented December 17, 1918. But it is to be understood that this spring arrangement is not limited in application to this particular impulser but may be used with other devices of this character.

In the drawings:

Fig. 1 is a perspective view showing a portion of a magneto to which my new impulse device is attached;

Fig. 2 is an elevation of the same with the rotatable driving member removed, showing the fixed cam member, and showing in dotted lines the relative location of the circular driving, pawl carrying member in one position;

Fig. 3 is a view looking at the inside of the removed, rotating driving member, showing in dotted lines the relative location of the fixed cam; the view being taken on the plane indicated by the dotted line 3—3 of Fig. 4;

Fig. 4 is a sectional view taken on the plane indicated by line 4—4 of Fig. 1;

Fig. 5 is a sectional view taken on line 5—5 of Fig. 4; and

Fig. 6 is a sectional view taken on line 6—6 of Fig. 4.

Referring to that embodiment of my invention shown in the accompanying drawings, the casing A of the magneto contains the usual horse-shoe magnets, armature, and the like, not shown, and a journal bearing "a" for the armature or magneto shaft B. The shaft B is preferably provided with a tapered portion "b" and a threaded end portion "b'." C is a drive shaft connected by suitable coupling D with the coupling D', the latter being secured to or integral with a rotatable driving member 10.

A stationary part 1 is provided with an outwardly projecting flange 2, and is secured with cam member 3 to the magneto frame A by means of screws 4 (see Fig. 2). A rotatable driven member 5, of disk form, provid-

ed with an apertured bearing hub 6, is secured to the armature shaft B by the key 7. As shown in the drawing, the aperture of the driven member 5 and a portion of the 5 aperture of its bearing hub 6, are tapered to fit over the correspondingly tapered portion "b" of the shaft B. A spanner lock nut 8, provided with a hub 9, is interiorly screw threaded for engagement with the threaded 10 end "b" of the shaft, the diameter of the nut being greater than the diameter of the end of the hub bearing 6 so as to have overlapping engagement with the driving member 10. The nut 8 being thus locked by the 15 screw threads onto the armature shaft and the driven member 5 and its hub 6 being keyed to said shaft, said three parts rotate together and at the same time the nut 8 bearing against the face of the driving member 20 10 holds the latter in place. In practice, I recommend a small clearance, say .005 of an inch between the end of the hub 6 and the adjacent surface of the nut 8. The external diameter of the hub 9 is such as to afford 25 bearing engagement thereof within the untapered apertured portion of the hub 6 of the driven member 5.

The driving member 10 is provided with an inwardly extending flange 11 recessed at 30 12 to receive the flange 2 of member 1, as shown in Fig. 4. Driving member 10 is provided with a hub 13 journaled on hub 6 of driven member 5. Driving member 10 carries stud 14 extending toward the magneto 35 and spaced from a stud 17 extending from the magneto and supported by the driven member 5.

Within the annular space enclosed by members 5 and 10 is located a volute spring 40 15 having one end 15^a formed to engage the studs 14 and 17 and the other end 15^b attached to a spring support 16 having a portion 16^a arranged to engage studs 14 and 17, so that in effect portion 16^a is a continuation 45 of spring 15. Support 16 is loosely journaled on hubs 6 and 13 and is provided with an aperture 16^b through which the spring 15 is threaded. When the spring 15 is in the position shown in Fig. 6 it is in an initial state of stress, the members 15^a and 16^a pushing in opposite directions against studs 50 14 and 17.

On that side of the driven member or disk 5, opposite that carrying the stud 17, are 55 two studs or pins 18, 18. Each of said pins affords a pivotal bearing support for a locking pawl 19, suitably apertured to fit over said pin. Each pawl 19, at its outer end, is provided with a lug 20, adapted to engage the cam 3. The cam 3 is provided on its peripheral margin with a cut away portion 21 which terminates in a cam-shoulder 22. The lug 20 of the pawl is adapted, at certain periods in the movement hereinafter described, 60 to fall into the cut-away portion 21 and to

have locking engagement with the cam-shoulder 22, as clearly indicated in Figs. 2 and 5.

23 is an apertured yoke, loosely and relatively mounted upon a bearing shoulder 24 70 of the armature shaft bearing. Said yoke is provided with radially, outwardly and diametrically oppositely extending arms 25, the outer ends of said arms are set in and have engagement with suitable recesses 26 75 in the reduced end 12 of the wall 11 of the driving member 10.

The operation of my invention is as follows: Shaft C is rotated clockwise, looking toward the magneto, and driving member 10 80 is rotated thereby through couplings D D'. As member 10 rotates stud 14 presses against portion 16^a of spring support 16 and motion is transmitted through spring 15 to stud 17 causing driven member 5 to rotate clockwise. The driving and driven members will be simultaneously rotated, until the outer end 20 85 of one of the pawls 19, swinging upon its stud 18, drops into the cut-away space 21 of the fixed cam 3 and comes into contact with the cam shoulder 22. When the lug 20 is thus engaging the non-rotatable cam shoulder 22, and the driven member 5 is thus arrested, the rotary forward movement of the driving member 10 continues, though momentarily retarded in its speed by the resisting action of the spring 15 when stressed in addition to its initial stress. The continued rotation of the driving member 10, however, presently brings one of the arms 25 of the yoke 23 into a position when the pawl 19 is lifted by said arm from the cam-shoulder 22. Thereupon the spring 15 will 90 immediately expand into its normal position 95 with the effect of causing the momentarily retarded but now released driven member 5 to again move forward in its path of rotation, and with an accelerated motion, as compared with the speed of rotation of the driving member 10; and thus, so to speak, catch up with the driving member 10.

This momentary retarding of the forward movement of the driven member 5 continues while the driving member 10 travels over an area for example of 32 degrees. Thus the current flow or spark is produced at the proper and predetermined moment of time. A similar action takes place with respect to the second pawl 19, as the revolution 100 of the driving member 10 continues. It will be understood that while the driving member 10 is making one complete revolution, the retarding, and then the accelerated forward movement of the driven member and the magneto shaft will take place twice. There are thus produced two impulses for 105 each single revolution of the shaft, corresponding to the two explosion strokes of a four cylinder engine.

When the driven member 5 is released in 110

the manner described the spring 15 delivers its stored energy to member 5 and to the magneto rotor connected therewith causing these parts to rotate with a speed higher than the speed of shaft C during the engine starting operation. These driven parts acquire considerable momentum and they not only catch up with the driving member 10 but tend to run ahead of member 10. At the instant these driven parts run ahead of member 10, the stud 17 will strike the spring support portion 16^a and spring end 15^a will strike against stud 14, and the energy of rotation of said driven parts will be taken up in the spring as it is again stressed beyond normal when stud 17 tends to run ahead of stud 14. In this manner spring 15 acts as a shock absorbing or energy absorbing spring during the time the motion of the driven parts is approaching in value the speed of the shaft C. It is apparent that in effect both ends of spring 15 transmit pressure to the studs 14 and 17. When spring 15 is being stressed above normal in winding it up for impulsing the magneto shaft, stud 14 moves ahead of stud 17 and parts 15^a and 16^a separate. Then when the driven parts are released stud 17 runs ahead of the stud 14 and parts 15^a and 16^a are again separated. In this way the one volute spring 15 acts as an impulse spring and as a cushioning spring to relieve the armature rotor of stresses resulting from the retarding of its movement after the impulse.

Another of the advantages resulting from the present invention is that the spring 15 may function with very little resistance due to friction. The spring itself is not engaged by the walls of its enclosure, and the only friction present is slight friction between spring support 16 and the hubs 6 and 13.

Obviously when the engine becomes self-operative and the speed of shaft C exceeds a certain amount, the pawls 19 will be held away from the cam 3 by centrifugal force and the device will no longer operate as an impulse coupling.

While the form of mechanism herein shown and described constitutes a preferred form of embodiment of the invention, it is to be understood that other forms might be adopted, all coming within the scope of the claims which follow.

55 What I claim is as follows:—

1. In an impulse coupling, the combination with driving and driven members; of means for temporarily retarding then releasing said driven member; a volute spring for effecting an operative connection between said driving and driven members; studs carried by said driving and driven members, respectively; and devices for causing said studs to receive pressure from either of the ends of said spring, including a part

attached to the inner end of said spring and adapted to engage said studs.

2. In an impulse coupling, the combination with driving and driven members one of which is provided with a hub; studs carried by said driving and driven members, respectively; of means for temporarily retarding then releasing said driven member; a volute spring for effecting an operative connection between said driving and driven members; a spring support loosely journaled upon said hub having a part extending outwardly to engage said studs and attached to the inner end of said spring; and means for causing said studs to receive pressure from the outer end of said spring.

3. In an impulse coupling, the combination with driving and driven members; of means for temporarily retarding then releasing said driven member; a volute spring for effecting an operative connection between said driving and driven members; studs carried by said driving and driven members, respectively; a spring support rotatably mounted coaxially with said members and attached to the inner end of said spring and having a part extending outwardly and apertured to receive the turns of the spring; and means for causing said studs to receive pressure from the outer end of said spring.

4. In an impulse coupling, the combination with driving and driven members; of means for temporarily retarding then releasing said driven member; half circular studs located with their flat, parallel faces adjacent, carried by said driving and driven members, respectively; a spring support rotatably mounted coaxially with said members, said support having an outwardly extending portion adapted to bear against said studs; and a volute spring having its outer end adapted to bear against said studs and its inner end attached to said spring support.

5. In an impulse coupling, the combination with driving and driven members; of means for temporarily retarding then releasing said driven member; studs carried by said driving and driven members respectively; a hub provided by one of said members; a spring support providing a bearing journaled on said hub and having a part extending outwardly to engage said studs, and a volute spring having its outer end adapted to bear against said studs and its inner end attached to said spring support.

In testimony whereof I hereto affix my signature.

RONALD K. EVANS.
